FOOTWEAR LAST AND METHOD OF ASSEMBLY THEREON

Leslie H. L'Hollier, Newton, Mass., assignor to
The B. F. Goodrich Company, New York, N. Y.,
a corporation of New York

Application June 29, 1951, Serial No. 232,542

10 Claims. (Cl. 12—141.)

1

This invention relates to a footwear and last assembly and pertains more particularly to a last upon which footwear may be assembled and a method of making footwear.

It is an object of this invention to provide a last upon which footwear having a gusset-type expansion member may be constructed.

It is also an object of this invention to provide a last adapted to maintain a gusset-type expansion member in an article of footwear mounted on the last in a normal folded or closed condition.

Another object of this invention is to provide a convenient and economical method of forming a gusset-type expansion member in articles of footwear.

Other objects of this invention will be apparent from the description and drawings which follow.

In the construction of certain articles of footwear, such as boots, overshoes, gaiters and the like, it has been found desirable to incorporate therein an expansion member for the purpose of permitting the article of footwear to be easily pulled on or removed from the foot and yet providing an article of footwear which is capable of closely encompassing the foot while it is being worn. A gusset-type expansion member constructed in the upper of a boot or shoe has proven particularly satisfactory not only from the standpoint of convenience in putting on and removing the boot or shoe but also because a gusset-type expansion member may be formed as an integral portion of the upper of the boot or shoe whether it be constructed in the front, back or side portion of the upper providing an upper which may be free of openings and waterproof, if the material from which the upper is made is waterproof.

Conventional methods of forming a gusset in a boot or shoe have not been entirely satisfactory, however, since they are time-consuming and expensive and frequently the gusset is distorted subsequent to its being "folded" to the desired contour rendering the boot or shoe unsatisfactory and unmarketable. For example, one method of forming a gusset in a boot or shoe constructed of a vulcanizable rubber material which may be reinforced with fabric includes forming the upper of the boot or shoe into a configuration conforming to the contour of a foot, slitting the upper along a zone which is desired to be expandible and stitching an expansion gusset to the margins of the slit portion of the upper, a method which is expensive and time-

consuming. Another method frequently employed in forming a gusset in a boot or shoe constructed of vulcanizable rubber material which may be reinforced with fabric comprises "folding" the gusset into the preformed upper and vulcanizing the rubber material molding it into a permanent configuration. This latter method of forming a gusset in a boot or shoe is not completely satisfactory, however, in that the gusset is frequently distorted from its desired configuration during the vulcanization operation, no positive method being provided for maintaining the gusset in the desired configuration during this operation, rendering the article unsatisfactory and unmarketable.

My invention attains the objectives set forth above and eliminates the deficiencies of heretofore known methods of forming a gusset in footwear by providing a last upon which the boot or shoe is constructed which maintains the gusset in the desired configuration at all times during the vulcanizing or setting operation providing footwear of the gusset type which is pleasing in appearance and capable of closely encompassing the foot of the wearer.

For a clearer understanding of this invention one embodiment of the invention is shown and described, however it will be understood that it is merely for the purpose of illustration and that I do not intend to limit this invention to this embodiment.

In the drawings:

Fig. 1 is a front elevation view of a gaiter assembled on a last embodying this invention;

Fig. 2 is a side elevation view partly broken away of the assembly of Fig. 1;

Fig. 3 is an enlarged section on line 3—3 of Fig. 2;

Fig. 4 is a perspective view of an auxiliary form member within the purview of this invention; and

Fig. 5 is a plan view of the last of Fig. 1.

As shown in the drawings, a gaiter 10 adapted to cover the foot and ankle of the wearer is mounted on a last 11 resembling in contour a foot and the general contour of gaiter 10.

Gaiter 10 is constructed of a flexible resilient rubbery material 12 reinforced with fabric 13, such as a square-woven fabric material, and has included in its upper 14 a gusset 15 which enables upper 14 to be extended, facilitating the wearer in pulling on and removing gaiter 10 from the foot. Gusset 15 extending over the instep portion of gaiter 10, as shown in Fig. 3, consists

of a pocket formed by folding a portion of upper 14 back upon itself.

Last 11 upon which gaiter 10 is assembled may be constructed of any material conventionally used in fabricating lasts or forms for footwear, such as cast metal compositions, and is formed in the general contour of a foot. In the present embodiment of this invention last 11 is provided with a pair of relatively rigid rods or restraining members 16, 16 which are detachably secured to last 11, one end 17 of each rod 16 being bent to fit into an opening 18, 18 in the upper marginal portion of last 11 and the other end 29 of each rod 16 being inserted in opening 20 centrally located at about the mid-vamp portion 21 of last 11 and adjacent to and directly beneath the apex 22 of gusset 15. As shown in Fig. 3, each rod 16 extends through a fold 23, 23 of gusset 15 along the invaginating edge 24 thereof continually urging each fold 23 toward the other and toward last 11 maintaining gusset 15 in a normal closed condition, rods 16, 16 being preferably formed of a springy material, such as spring steel or drawn metal wire.

A relatively stiff auxiliary form member 25 disposed between folds 23, 23 and midportion 26 of gusset 15 and held securely in place by rods 16, 16 imparts the desired contour to midportion 26 of gusset 15 and provides edges 27, 27 around which upper 14 may be folded in forming gusset 15. Form member 25 may be formed of any relatively rigid material such as metal, fabric or paper reinforced and stiffened with an appropriate sizing material, or the like.

A preferred method of constructing gusset-type footwear within the purview of this invention is to drape the preformed upper 14 over last 11 and last a sole member 28 to the bottom margins of upper 14. Form member 25 is positioned over the portion of upper 14 which constitutes midportion 26 of gusset 15 and upper 14 is folded around form member 25 and folded back on itself to produce folds 23, 23, as shown in Fig. 3. A rod 16 is extended between the opposing faces of each fold 23 and the lower ends 29, 29 of rods 16, 16 are inserted in opening 20. The other end 17 of each rod 16 is then inserted in the appropriate opening 18, as shown in Fig. 1, and the assembly is vulcanized to mold the gaiter into the desired configuration.

During the molding or vulcanizing operation the gusset is maintained in its normally closed configuration until the rubbery material included in the gusset is vulcanized to a desired state after which the rods and form member may be removed and the gaiter stripped from the last. The vulcanizing process permanently molds the gusset to a configuration normally biased towards a closed condition, as shown in Fig. 3, without additional reinforcement being required, although suitable securing means 30 may be constructed in upper 14 in the usual manner, so that the gusset will be maintained in a closed condition as the wearer distorts the upper in walking.

My invention provides a method of forming a gusset in an article of footwear which insures that the gusset will not be distorted from its desired contour during the vulcanization or molding process providing an article pleasing in appearance and readily marketable.

A last for building footwear within the purview of this invention provides a method of conveniently and economically forming a gusset in a boot or shoe upper.

It is clear that obvious variations and modifica-

tions of this invention may be made without departing from the spirit and scope of this invention as defined in the appended claims.

I claim:

- 5 1. A last for footwear comprising a body member having the general contour of an article of footwear, and at least one relatively rigid elongated restraining member extending externally along the face of said body member from its upper portion to its lower portion, each end of each said restraining member being detachably secured to said body member.
- 10 2. A last for footwear comprising a body member having the general contour of a foot, at least one relatively rigid elongated restraining member extending externally along the face of said body member from its upper portion to its lower portion, means for securing an end of each said restraining member to said upper portion of said body member, and means for securing the opposite end of each said restraining member to said lower portion of said body member.
- 15 3. A last for footwear comprising a body member having the general contour of an article of footwear, and a pair of relatively rigid elongated restraining members extending externally along the face of said body member from its upper portion to its lower portion, the ends of each said restraining member being detachably secured to said body member.
- 20 4. A last for footwear comprising a body member having the general contour of a foot, a pair of relatively rigid elongated restraining members extending externally along the front face of said body member from its upper marginal portion to about its mid-vamp portion, means for securing the upper ends of said restraining members to the upper marginal portion of said body member, and means for securing the opposite ends of said restraining members to said body member at about its mid-vamp portion.
- 25 5. A last for footwear comprising a body member having the general contour of an article of footwear, said body member having a centrally located opening in its front face at about mid-vamp height and having a pair of openings in the front face of its upper marginal portion spaced one on either side of said body member, and a pair of relatively rigid elongated rod-like restraining members extending externally along the front face of said body member in a converging relationship from the said upper marginal portion of said body member to about the mid-vamp portion of said body member, the upper end of one said restraining member extending into one of said openings located in said upper marginal portion and the upper end of the other said restraining member extending into the other said opening located in said upper marginal portion and the lower ends of said restraining members both extending into the said opening in the front face of said body member centrally located at about mid-vamp height.
- 30 6. The method of making an article of footwear having a gusset therein which comprises assembling over a last an upper member having an outwardly flared portion, disposing a relatively rigid auxiliary form member over the portion of said upper member which forms the midportion of said gusset, folding said upper member over the outer face of said form member to form the folds of said gusset, disposing a relatively rigid elongated restraining member between the opposing faces of each said fold along its invaginating margin, and securing one end of each said re-
- 35 7. The method of forming a gusset in an article of footwear which comprises forming a gusset in an upper member having an outwardly flared portion, disposing a relatively rigid auxiliary form member over the portion of said upper member which forms the midportion of said gusset, folding said upper member over the outer face of said form member to form the folds of said gusset, disposing a relatively rigid elongated restraining member between the opposing faces of each said fold along its invaginating margin, and securing one end of each said re-
- 40 8. The method of forming a gusset in an article of footwear which comprises forming a gusset in an upper member having an outwardly flared portion, disposing a relatively rigid auxiliary form member over the portion of said upper member which forms the midportion of said gusset, folding said upper member over the outer face of said form member to form the folds of said gusset, disposing a relatively rigid elongated restraining member between the opposing faces of each said fold along its invaginating margin, and securing one end of each said re-
- 45 9. The method of forming a gusset in an article of footwear which comprises forming a gusset in an upper member having an outwardly flared portion, disposing a relatively rigid auxiliary form member over the portion of said upper member which forms the midportion of said gusset, folding said upper member over the outer face of said form member to form the folds of said gusset, disposing a relatively rigid elongated restraining member between the opposing faces of each said fold along its invaginating margin, and securing one end of each said re-
- 50 10. The method of forming a gusset in an article of footwear which comprises forming a gusset in an upper member having an outwardly flared portion, disposing a relatively rigid auxiliary form member over the portion of said upper member which forms the midportion of said gusset, folding said upper member over the outer face of said form member to form the folds of said gusset, disposing a relatively rigid elongated restraining member between the opposing faces of each said fold along its invaginating margin, and securing one end of each said re-
- 55 11. The method of forming a gusset in an article of footwear which comprises forming a gusset in an upper member having an outwardly flared portion, disposing a relatively rigid auxiliary form member over the portion of said upper member which forms the midportion of said gusset, folding said upper member over the outer face of said form member to form the folds of said gusset, disposing a relatively rigid elongated restraining member between the opposing faces of each said fold along its invaginating margin, and securing one end of each said re-
- 60 12. The method of forming a gusset in an article of footwear which comprises forming a gusset in an upper member having an outwardly flared portion, disposing a relatively rigid auxiliary form member over the portion of said upper member which forms the midportion of said gusset, folding said upper member over the outer face of said form member to form the folds of said gusset, disposing a relatively rigid elongated restraining member between the opposing faces of each said fold along its invaginating margin, and securing one end of each said re-
- 65 13. The method of forming a gusset in an article of footwear which comprises forming a gusset in an upper member having an outwardly flared portion, disposing a relatively rigid auxiliary form member over the portion of said upper member which forms the midportion of said gusset, folding said upper member over the outer face of said form member to form the folds of said gusset, disposing a relatively rigid elongated restraining member between the opposing faces of each said fold along its invaginating margin, and securing one end of each said re-
- 70 14. The method of forming a gusset in an article of footwear which comprises forming a gusset in an upper member having an outwardly flared portion, disposing a relatively rigid auxiliary form member over the portion of said upper member which forms the midportion of said gusset, folding said upper member over the outer face of said form member to form the folds of said gusset, disposing a relatively rigid elongated restraining member between the opposing faces of each said fold along its invaginating margin, and securing one end of each said re-
- 75 15. The method of forming a gusset in an article of footwear which comprises forming a gusset in an upper member having an outwardly flared portion, disposing a relatively rigid auxiliary form member over the portion of said upper member which forms the midportion of said gusset, folding said upper member over the outer face of said form member to form the folds of said gusset, disposing a relatively rigid elongated restraining member between the opposing faces of each said fold along its invaginating margin, and securing one end of each said re-

straining member to said last at a zone adjacent to and directly beneath the apex of said gusset and the opposite end of each said restraining member to said last at its upper marginal portion.

7. The method of making an article of footwear having a gusset therein which comprises disposing over a last a vulcanizable upper member having an outwardly flared portion, disposing a relatively rigid form member having the general contour of the midportion of said gusset over the portion of said upper member which forms the midportion of said gusset, folding said upper member over opposing edges and over the outer face of said form member to form the opposing folds of said gusset, disposing a relatively rigid elongated rod-like restraining member between the opposing faces of each said fold along its invaginating margin, inserting one end of each said restraining member in an opening in said last at a zone adjacent to and directly beneath the apex of said gusset and inserting the other end of each said restraining member in separate spaced openings in the upper marginal portion of said last, and vulcanizing the assembly.

8. The method of making an article of footwear having a gusset extending over the instep portion of said article terminating at about mid-vamp height which comprises disposing over a last a vulcanizable upper member having an outwardly flared instep portion, disposing a relatively rigid auxiliary form member having the general contour of the midportion of said gusset over the outer face of the portion of said upper member which forms said midportion of said gusset, urging said form member against said last over the instep portion thereof with said midportion of said gusset interposed therebetween and in contacting relationship with said last, folding said upper member over opposing margins and over the outer face of said form member to form the opposing folds of said gusset, disposing a relatively rigid elongated rod-like restraining member between the opposing faces of each said fold along its invaginating margin, inserting the lower end of each said restraining member in an opening centrally located in said last at about mid-

vamp height and adjacent to and directly beneath the apex of said gusset and inserting the other ends of said restraining member in separate openings located in the upper marginal portion of said last spaced one on either side of said last, and vulcanizing the assembly.

9. The method of making an article of footwear having a gusset therein which comprises assembling over a last a vulcanizable upper member having an outwardly flared portion and including a vulcanizable rubbery material, disposing a relatively rigid form member over the portion of said upper member which forms the midportion of said gusset, folding said upper member over the outer face of said form member to form the folds of said gusset, disposing a relatively rigid elongated restraining member between the opposing faces of each said fold along its invaginating margin, securing one end of each said restraining member to said last at a zone adjacent to and directly beneath the apex of said gusset and the opposite end of each said restraining member to said last at its upper marginal portion, and vulcanizing the assembly.

10. A last for footwear comprising a body member having the general contour of an article of footwear and a pair of relatively rigid elongated restraining members extending externally along the front face of said body member from its upper marginal portion to about its mid-vamp portion and converging toward each other as they extend from said upper to said lower portions of said body member, the ends of each said restraining member being detachably secured to said body member.
